Primary Examiner — Barbara Fox*Assistant Examiner* — Jamaal Rasheed(74) *Attorney, Agent, or Firm* — Haynes and Boone, LLP(57) **CLAIM**

The ornamental design for a bonfire pit stand, as shown and described.

DESCRIPTION

FIG. 1 is a top front isometric view of a bonfire pit stand showing my new design;

FIG. 2 is a front elevational view thereof, the back elevational view is a mirror image of the front elevational view;

FIG. 3 is a right elevational view thereof, the left elevational view is a mirror image of the right elevational view;

FIG. 4 is a top plan view thereof, the bottom plan view is a mirror image of the top plan view; and,

FIG. 5 is a cross-sectional view thereof taken along the direction indicated in FIG. 4.
